UNITED STATES PATENT OFFICE

2,611,203

HIGHWAY SIGN

William J. Taylor, John H. Worsham, and
John L. Davis, Oakland, Calif.

Application March 27, 1950, Serial No. 152,023

2 Claims. (Cl. 40—126)

1

This invention relates to the control of vehicular traffic on highways or other thoroughfares.

An object of the invention is to provide means and a method for deterring operation of vehicles in an erratic manner or at excessive speeds on sections of roads where such operation might endanger the safety of others.

An additional object of the invention is to provide a device of the character described which is arranged to be clearly perceptible to the operators of vehicles travelling over a section of highway and which is suggestive of the immediate presence of a law enforcement officer.

Another object of the invention is to provide facsimile reproductions of official vehicles of a law enforcement agency arranged to be displayed to oncoming traffic in a road section to be controlled and at such a distance that potential traffic law violators will be discouraged from attempting or committing any infractions in the particular road section due to uncertainty as to whether or not the visible object ahead is an actual police vehicle.

A further object of the invention is to provide a focal plane facsimile reproduction as above described which is fully as large as, and capable of visually obscuring, an actual vehicle which may be positioned adjacent and in prescribed registry with the reproduction.

The invention possesses other objects and features of advantage, some of which, with the foregoing, will be set forth in the following description of the preferred form of the invention which is illustrated in the drawing accompanying and forming part of the specification. It is to be understood, however, that variations in the showing made by the said drawing and description may be adopted within the scope of the invention as set forth in the claims.

Referring to the drawing:

Figure 1 is a view, pictorial in character, showing the appearance of the vehicle counterpart of our invention to the driver of an approaching vehicle.

Figure 2 is a perspective view showing the vehicle counterpart structure in use to shield an actual law enforcement vehicle from the view of rearwardly approaching drivers.

Figure 3 is a front elevational view of the traffic control apparatus of our invention.

Figure 4 is a side elevational view of the structure shown in Figure 3.

Traffic law violators particularly habitual or occasional speeders or reckless drivers are becom-

2

ing more and more difficult to detect and apprehend due to the fact that new road construction and the number of vehicles coming into use are fast outstripping the growth of local and state highway patrol forces with the result that in areas where the ratio of road length to patrol personnel is high safety regulations are being constantly flaunted by potentially dangerous drivers and many accidents occur oftentimes with serious or fatal consequences for innocent parties involved. In instances where numerous accidents or violations occur it has often been found necessary to station official vehicles in or near the road section so as to apprehend violators or to provide suggestive warning to discourage any infraction of traffic rules. This method of traffic control, while effective in the particular road area too greatly restricts the general patrol coverage of the thoroughfare with the result that violations cannot be effectively curbed in adjacent or other road sections. We have evolved simple and effective means, as will hereinafter be described, whereby the enforcement efficiency of a comparatively small patrol force may be spread over a considerable length or network of roads and which permits units of the force to more effectively watch particular sections of the road or to trail or apprehend vehicles which are being driven in potentially dangerous manners.

In the form in which we have chosen to illustrate our invention, we provide at least one but preferably two panel members 6 of wood, sheet metal or other suitable material each having a marginal contour 7 shaped to conform exactly with the medial transverse contour of a full size official law enforcement vehicle and provided on the facial surface 8 thereof with a photographic or other exact pictorial representation of such vehicle. Preferably the said surface and pictorial representation are overlaid with gloss paint precisely matching the color areas representing the vehicle bumper 9 and other metal trim may be given coatings of highly reflective silvery metallic paint or may be overlaid with strips of aluminum or other metal foil suitably bonded or otherwise attached to the panel. For added reality, the areas of the panel depicting the tail-lights 11 and caution lights 12 of the official vehicle may be equipped with light reflectors positioned behind red glass or transparent plastic lenses, the lenses and reflectors being suitably secured in apertures or recesses formed in the panel members.

For additional realism, a rod member 13 suit-

ably seated or otherwise secured at its lower end in a socket 14 formed on the panel margin may be provided to indicate the radio antenna characteristically present on most law enforcement vehicles.

Suitable means may be provided for supporting the panel 6 in a planar vertical position but we prefer to utilize a particular type of support which lends reality to the device. Secured to and extending downwardly from the bottom portion of the panel 6 is a pair of laterally spaced vertical posts 18 or equivalent members spaced apart a distance equivalent to the center to center spacing between the tire treads of the actual vehicle and preferably embedded in the soil of a road shoulder where it is desired to display the traffic control device. The posts 18 are made of wood or other suitable material which has a facial width equivalent to the tread width of the actual vehicle tire and painted or otherwise inscribed on the posts are pictorial representations 19 of the tire tread design. It will be noted that the posts are embedded in the ground or are so otherwise supported that the portions thereof exposed above the ground level and interposed between the latter and the bottom edge of the panel member 6 are equal in vertical length to the portions of tires visually exposed below an actual vehicle. Thus a person viewing the device frontally from a distance will have considerable difficulty distinguishing the control device from an actual vehicle since the device permits an unobstructed view under and around it except for the posts representing the vehicle tires.

In use, one or more of the traffic control devices are set up at spaced points along a highway or other thoroughfare, preferably on the off-pavement shoulder thereof by the law enforcement agency assigned to regulate traffic on such thoroughfares and are arranged so as to present preferably a rear view of the depicted official vehicle toward oncoming traffic. Invariably, any driver who may be unlawfully speeding or otherwise operating his vehicle in a reckless manner, upon sighting the supposed law enforcement vehicle parked along the road ahead will immediately slow down to permitted speed or will otherwise conduct himself in a lawful manner. Thus if the control device is placed just beyond a zone in which speed or other regulations are being continually flaunted, effective control of traffic may be secured without requiring the presence of a law enforcement officer. Although it is possible that habitual users of a particular highway may soon learn that a certain traffic control device is an artifice, the portable character of the device permits it to be removed from its set location from time to time and replaced by an actual vehicle manned by a law enforcement officer so that those drivers who disregard the warning afforded by the control device may be apprehended. It will also be seen

in Figure 2 that since the replica is equal in size to an actual enforcement vehicle and possesses the same contour thereof, the former is capable of fully concealing an actual vehicle 16 which may be backed up to the replica so that the latter will be interposed between the actual vehicle and the oncoming vehicles 17 in the immediately adjacent traffic lane. Thus a motorist familiar with the replica and its location may ignore the warning and speed or otherwise erratically drive past only to be apprehended by the officer manning the actual enforcement vehicle.

We claim:

1. Apparatus for controlling highway traffic comprising a panel member bearing a full-size pictorial representation of portion of an actual law enforcement vehicle, and means secured to and depending from said panel member and engaged with an off-pavement portion of a roadway in a position facing at least one flow of vehicular traffic on said roadway, said means having a lateral width substantially equal to the tread width of a tire of said actual vehicle and being spaced apart substantially equal to the lateral tread spacing of the actual vehicle tires, said panel member being peripherally contoured to conform with the external periphery of said portion of the actual vehicle.

2. Apparatus for controlling highway traffic comprising a panel member bearing a full size pictorial representation of portion of an actual law enforcement vehicle, support members secured to and depending from said panel member and engaged with an off-pavement portion of a roadway in a position facing at least one flow of vehicular traffic on said roadway, said support members each having lateral width equal to the tread width of a tire of said actual vehicle and further being spaced apart equal to the lateral tread spacing of the actual vehicle tires, and a pictorial representation of a tire tread on each of said support members and facing said flow of vehicular traffic on said roadway.
